UNITED STATES PATENT OFFICE

159,331

DISPLAY BOX FOR CRAYONS AND THE LIKE

Joseph C. Foster, Leominster, Mass., assignor to Foster Grant Co., Inc., Leominster, Mass., a corporation of Massachusetts

Application November 18, 1949, Serial No. 6,126

Term of patent 14 years

(Cl. D58—11)

To all whom it may concern:

Be it known that I, Joseph C. Foster, a citizen of the United States, residing at Leominster, Worcester County, and State of Massachusetts, have invented a new, original, and ornamental Design for a Display Box for Crayons and the like, of which the following is a specification, reference being had to the accompanying drawings, forming a part thereof, in which:

Figure 1 is a front plan view of a display box for crayons and the like, showing my new design;

Fig. 2 is a rear plan view of the box;

Fig. 3 is a longitudinal side view of the box;

Fig. 4 is an end view;

Fig. 5 is a view showing the filler laid out flat, and

Fig. 6 is a vertical section taken on the line 6—6 of Fig. 1.

The dotted lines shown in the drawing are for illustrative purposes only.

I claim:

The ornamental design for a display box for crayons and the like, substantially as shown and described.

JOSEPH C. FOSTER.
